UNITED STATES PATENT OFFICE.

ANTON MASLÉ, OF LAIBACH, AUSTRIA-HUNGARY.

DEVICE FOR USE IN DRESSING THE HAIR.

1,078,055.

Specification of Letters Patent.

Patented Nov. 11, 1913.

Application filed January 6, 1912. Serial No. 669,739.

To all whom it may concern:

Be it known that I, ANTON MASLÉ, residing at Jakober trg. 8, Laibach, Carniola, (Krain,) Austria-Hungary, have invented 5 certain new and useful Improvements in Devices for Use in Dressing the Hair, of which the following is a specification.

This invention relates to devices for dressing the hair.

10 The device consists of two combs, the handle portions of which are connected along their longer edges by means of a hinge, so that the combs can be closed together or opened out to a predetermined extent in 15 order that they may spread apart and form a species of roof-like supporting structure.

In the accompanying drawing: Figure 1 is a front view of a hair dressing device embodying my invention, and Fig. 2 a section on line A—B, Fig. 1.

20 The handle portions *a* of the two combs *b* are connected together by a hinged clamping device.

25 *e* is an expansile spring located upon the pin *h* connecting two parts *c d* of the hinged device and arranged between these parts in such a way that it has a tendency to open them out so that the combs *b* are spread apart.

30 One extremity of each of the hinged pieces is adapted to embrace the handle *a* of the comb *b* and to hold it fast and in such a way that it can be easily removed. The other end of each piece *c d* limits the opening of the parts. A regulating screw *f* serves to regulate the amount of the opening of the combs *b*. By closing the portions *c d* together, the combs *b* are first brought together and in this condition the device is 40 pushed into the hair at the place where the hair is to be made up. When the device

is released the combs spread apart and raise up the hair which remains permanently in the raised position without using the ordinary devices. It is moreover retained in 45 a position corresponding to the angle which the two combs are to make with one another. The size of this angle can be varied to suit requirements by means of the regulating screw *F*. 50

It will of course be understood that the combs *b* can be permanently attached to the hinged devices *c d*, and that the clamping device and the spring *e* and regulating screw *f* can be formed and arranged in 55 many other ways without departing from the principle of the invention.

I claim—

1. In a device for dressing the hair, the combination of two combs, a hinge each 60 member of which is provided with a clip, a comb carried by each clip, spring means for normally pressing the combs apart, and means for limiting the extent to which they can be separated under the influence of the spring substantially as described. 65

2. In a device for dressing the hair the combination of two combs, a bent spring device for connecting the combs at the back 70 and normally tending to separate the said combs and screw means limiting the extent to which they can be separated and thus regulating the opening between them substantially as described. 75

Dated this 20th day of December 1911.

In testimony whereof I affix my signature in presence of two witnesses.

ANTON MASLÉ.
